TISSUE DISPENSER HOLDER

Arend M. Roskamp, 650 Constance Lane; Gresham R. Roskamp, 634 Westgate; and Robert G. Roskamp, 3005 Ierman, all of Deerfield, Ill. 60015

Filed Jan. 19, 1971, Ser. No. 107,873

Term of patent 14 years

Int. Cl. D8—08

U.S. Cl. D8—233

FIG. 1 is a perspective view of a tissue dispenser holder showing my new design;

FIG. 2 is a rear elevational view thereof;

FIG. 3 is a view with portions in section and elevation taken on the plane of the section line 3—3 of FIG. 2, looking in the direction of the indicating arrows; and

FIG. 4 is an edge elevational view thereof.

The broken lines are for illustrative purposes only.

We claim:

The ornamental design for a tissue dispenser holder, as shown and described.
